UNITED STATES PATENT OFFICE.

MOSES G. CRANE, OF NEWTON, MASSACHUSETTS.

INDICATOR FOR FIRE-ALARM PURPOSES.

SPECIFICATION forming part of Letters Patent No. 273,083, dated February 27, 1883.

Application filed December 3, 1881. (No model.)

To all whom it may concern:

Be it known that I, MOSES G. CRANE, of Newton, county of Middlesex, State of Massachusetts, have invented an Improvement in 5 Indicators for Fire-Alarm Purposes, of which the following description, in connection with the accompanying drawings, is a specification.

This invention relates to an indicator for fire-alarm purposes, and is intended as an improvement in indicators of the class in which a series of figure-indicating devices or drums are controlled by the impulses employed in giving a fire-alarm to indicate the number of the said alarm, one drum being employed to indicate 15 each figure of the whole number of the alarm and a single tripping device being employed to govern the movements of all the said drums, its position being controlled by a time-train, so that it will operate upon the different drums 20 in turn when the proper interval occurs between the strokes of the alarm.

The present invention consists in improvements in the mechanical construction of the apparatus whereby it is rendered more certain 25 in operation and more convenient for use.

Figure 1 shows in front elevation an indicator constructed in accordance with this invention; Fig. 2, a side elevation of the upper portion thereof, showing the means employed 30 for operating the figure-indicating device; Fig. 3, a detail; Fig. 4, a modification to be referred to, and Fig. 5 a perspective view of one of the levers by which the movements of the figured drums are controlled.

35 The figure-indicating devices are shown as drums $a a' a^2$, each having the figures 1 to 9 in order at uniform distances on its periphery, and a corresponding blank space between the figures 1 and 9, the whole apparatus being, 40 when in use, inclosed in a case having a series of apertures or windows, through which one of the said figures on each drum may be seen when in proper position, these parts being common in indicators of this class. These drums 45 are pivoted on a shaft, 2, supported in the frame-work A, the hub of each drum having a pinion, b, (see Fig. 2,) meshing with an actuating device shown in Figs. 1 and 2, as a toothed bar, c, slotted at its lower end to embrace and

be guided by the said pinion, and guided at 50 its upper end in a slot in the frame-work A, the said bars being acted upon by springs c' , having a tendency to move them upward, and thus, through the pinions b , to turn the drums so as to bring the numbers from 1 to 9 successively behind the opening in the casing. 55

In Fig. 4 a segmental gear is employed instead of the bar c to operate the drums, it being the mechanical equivalent of the said bar, the preference depending upon the form of 60 frame-work and relative positions of the parts. The movement of the drums is controlled by the escapement-levers d , pivoted upon a shaft, 3, in the frame-work, and having pallets $d' d^2$, arranged to engage pins d^3 , projecting laterally 65 from the drums, one pin corresponding to each figure upon the face thereof. The levers d are provided with feet d^4 , actuated, as hereinafter described, to produce a vibration of one of the said levers d on its pivot at each stroke of the 70 alarm. When the lever d is thus raised the pin d^3 , held by it, escapes from the pallet d' , and is arrested by the pallet d^2 , as will be readily understood by referring to Fig. 2, and when the lever falls again under the action of 75 gravity, assisted by the spring d^5 , the said pin escapes from the pallet d^2 , and the drum rotates until the next pin is arrested by the pallet d' . By this arrangement the drum is permitted to move for the space of one figure, 80 and one only, each time the foot d^4 of the lever d is actuated.

A stop-pin, a^3 , connected with the side of each drum, serves by its engagement with the bar c to prevent the drum from moving forward farther than one complete rotation, and also serves as a stop to limit the backward movement thereof when the drums are restored to their normal position, indicating blank or zero, by the restoring-plate a^4 , pivoted at 4 upon the frame-work, and adapted, when moved downward by the rod a^5 , as hereinafter described, to engage the toothed bars and move them downward, rotating the drums $a a' a^2$ backward to their zero or normal position. 90 The faces of pallets $d' d^2$, engaged by the pins d^3 in this backward movement, are inclined, so as to permit the said pins to pass 95

readily, they then vibrating the arms d up and down.

The feet d^4 of the controlling or escapement levers d are operated by an actuating device 5 or trip-rod, e , connected with a wrist-pin, e' , carried by the main cam-shaft e^2 of a train of wheel-work, $f^1 f^2 f^3$, actuated in the usual manner by a spring or weight connected with the squared winding-shaft f^4 and governed by a 10 fan or fly, f^5 . The said main or cam shaft e^2 is provided with a detent-arm, e^3 , controlled by a projection, g , in the armature-lever g' , pivoted at 5 in such position that when the armature is retracted from its controlling-magnet 15 net g^2 the said projection g is disengaged from the arm e^3 , permitting the shaft e^2 to revolve, and in such revolution to throw the trip e upward, so that it will engage one of the feet d^4 of the escapement-levers d . In the said rotation 20 a cam, e^4 , on the hub of the arm e^3 engages a spring, g^2 , on an arm, g^3 , of the armature-lever, mechanically moving the armature up to the poles of its magnet, and a pin, e^5 , engages an armature-prop, e^6 , pivoted at 6 upon the 25 frame-work A, raising the said prop so that its end e^7 engages a pin, g^4 , on the end of the armature-lever g , as shown in dotted lines, and retains the said armature quite close to the poles of its magnet, so that but comparatively 30 small magnetic force will be required to attract the said armature. The action of the cam e^4 and pin e^5 is properly timed, so that the former first moves up the armature-lever, and the latter then moves up the prop and retains 35 it until the said cam e^4 has released the armature-lever, permitting it to engage and be held by the said prop, which is itself held by the armature-lever as long as it is under the influence of its retractor alone, having a tendency 40 to move the armature away from the magnet. As soon as the armature is attracted the pin g^4 is thereby moved out of engagement with the end e^7 of the prop e^6 , which drops by its own weight to the position shown in full lines, 45 Fig. 1, leaving the armature free to move back as soon as the magnet g^2 is again demagnetized. It will thus be seen that each time that the circuit, over which a signal is being sent is closed and then broken the shaft e^2 will be 50 permitted to make one revolution, and in so doing will restore the armature nearly to the poles of its magnet and raise the prop e^6 to retain it there until the circuit is again closed, and that in the said rotation of the shaft e^2 the 55 trip-rod e will be thrown upward to strike one of the feet d^4 of the escapement-levers of the figured drums. The upper end of the said trip e passes through a guide, h , carried upon an arm of a trip-controlling plate, i , which is frictionally held upon a shaft, j , of a gear, j' , meshing with the pinion upon the shaft of an escapement-wheel, j^2 , governed by a pendulum, j^3 , so as to have a uniform movement, the said 60 wheels constituting a train denominated the 65 "controlling time-train." The said shaft j has

loose upon it a pinion, j^4 , (see Fig. 3,) meshing with a segmental gear, j^5 , provided with an actuating-spring, j^6 , and a cam-roller, j^7 , resting upon a cam, e^8 , upon the shaft e^2 of the main train, so that at each rotation of the said shaft e^2 , as before described, the segmental gear j^5 is raised, stretching the spring j^6 . 70

The pinion j^4 is provided with a ratchet engaging a pawl on the gear j' , so that in the return movement of the segment j^5 under action of the spring j^6 , as soon as the high part of the cam e^8 has passed the roller j^7 , which occurs when the detent-arm e^3 is held, the time-train is set in motion by the force of the spring j^6 , carrying trip-controlling plate i with a uniform movement from left to right, Fig. 1. The speed of movement of the time-train is such that the rod e will be carried from one to the next of the feet d^4 in an interval of time, such as employed between the different series 85 of strokes representing the figures of the whole number of an alarm—as, for instance, that occurring between the three strokes and the four strokes of the alarm 3 4 5.

The trip-guiding plate i is provided with 90 teeth i' in proper position to be engaged by a pin, e^9 , on the hub of the arm e^3 in the rotation of the shaft e^2 , the said pin carrying the plate i back in the opposite direction to that in which it is moved by the time-train to such a point 95 that when the left-hand one of the said teeth is engaged by the said pin the trip-rod e in the same rotation of the shaft e^2 will strike the left-hand one of the feet d^4 , permitting the left-hand drum, a , to move for one space, as before 100 described, and when the next tooth i' is engaged the next foot and drum will be acted upon by the trip-rod, and so on. The plate i slips backward independently of the shaft j when thus actuated by the pin e^9 , and immediately after the arm e^3 has been arrested begins to travel under the action of the time-train, from the left-hand toward the right-hand one of the feet d^4 . If a short interval only 105 elapses between the successive relations of the shaft e^2 , such as employed between the different strokes representing one figure of a whole number, the tooth i' of the plate i that was last engaged will not be carried by the time-train beyond the range of the pin e^9 , so that 110 as long as the strokes occur at these definite short intervals the trip-rod e will always be carried back to the same spot and actuate the same one of the feet d^4 and figured drums, thus giving a series of movements of the same drum, 115 and causing it to show a figure the same as the number of the said movements. When, however, the long interval occurs the tooth i' last actuated will be carried beyond the range of the pin e^9 , and the end of the trip-rod e 120 will be carried to the next one of the feet d^4 , and in the next rotation of the shaft e^2 , after the said interval, the next tooth i' will be engaged by the pin e^9 , and the trip-rod e will be 125 brought back to a position under the said next 130

foot d^4 , so that the left-hand one of the drums will now remain stationary, indicating the number of the first series of blows for the first figure of the whole number of the alarm, while 5 the second drum will begin to be actuated to show the number of the next series of strokes, and after the next equally long interval the third tooth i' will be engaged by the pin e^9 and the third drum will be actuated. If the number 10 of the alarm should contain but one or two figures, the interval between the successive repetitions of the wheel-number is so much greater than that between the different figures of the same number that the succeeding tooth i' will be carried wholly beyond the range of 15 the pin e^9 , and only the first drum or first two drums will be actuated, as should be the case. After an alarm has been completed the apparatus is restored to its normal condition (shown 20 in Fig. 1) as follows: The drum-restoring plate or lever a^4 is connected by a rod, a^5 , with a similar lever or arm, a^6 , pivoted at the bottom of the frame-work, and provided with a suitable cord or handle, a^7 , extended out through 25 the case, so that by pulling down on the said handle the plate a^4 is depressed, thereby turning the drums back to their normal position, as before described.

The rod a^5 is provided with a tappet, a^8 , 30 which, when thus depressed, engages an arm, i^2 , of the trip-guide plate i , moving the end of the trip-rod e back to the proper position to engage the left-hand one of the feet d^4 , as is desired for giving the first figure of the next 35 alarm or signal that may be sent.

The range of movement of the plate i is limited by a stop-pin, l , upon the frame-work, and the pin g^4 upon the armature-lever.

The winding-up cam e^6 of the time-train is 40 of such height that the said train will run down in about the interval which occurs between the two rounds or repetitions of the same signal, so that the said train will usually be run down before the restoring devices a^8 45 a^5 a^6 are set back by the operator.

I claim—

1. In an indicator, the figured drums provided with stop-projections corresponding to the figures thereon, combined with pinions 50 connected with the said drums, toothed actuating devices meshing with the said pinions, means to move the said actuating devices to rotate the said drums, and mechanism co-operating with the said stop-projections, whereby the drums are arrested when moved to display the proper figure, substantially as described.

2. The combination, with the figured drum provided with projections corresponding in 60 position to the figures thereon, and actuating mechanism tending to rotate it in one direction, of the pivoted escapement-lever provided with two pallets, arranged to co-operate with the said projections in turn, whereby the said 65 drum is permitted to move for the space of

one figure only at each complete to-and-fro vibration of the said lever, substantially as described.

3. The combination of the following elements, namely: the figured drums, stop-projections corresponding to the figures thereon, pinions connected with the said drums, toothed actuating-bars, slotted to embrace and be guided by the said pinions, springs or equivalents for moving the said bars in one direction and restoring mechanism to move them in the other direction, and mechanism co-operating with the stop-projections, whereby the drums are arrested at the proper points when actuated by the bars moving under the influence of their springs, substantially as described. 75

4. The main cam-shaft, provided with a detent-arm combined with the armature lever, having a stop projector for the said detent-arm, and an arm to be engaged by a cam on the said shaft in its rotation, and the armature-propping device adapted to be engaged by a projection on the said shaft in its rotation, whereby at each rotation of the said 80 shaft the armature is restored to a position near the poles of its magnet, and the propping device moved up to retain it there, substantially as described. 85

5. The main cam-shaft, its wrist-pin, and 90 tripping-rod connected therewith, combined with the controlling guide-plate for the said tripping-rod, and its controlling time-train and actuating-spring therefor, the said main shaft being provided with a cam by which the said 95 spring is wound up to actuate the said time-train, substantially as described.

6. The figured drum and the trip-rod guide-plate, combined with the restoring mechanism for the said drum and guide-plate, whereby 100 both are set in their normal position, ready to receive a signal by a single operation, substantially as described.

7. The figure-indicating devices and controlling-levers therefor, combined with the 110 trip-rod, its controlling-plate frictionally connected with the shaft of a time-train, and provided with teeth and a guide for the said rod, and the main cam-shaft connected with the said rod, and provided with a projection co-operating with the teeth of the prop-controlling plate, substantially as described. 115

8. A series of figured drums arranged to turn separately and independently under the action of springs or their equivalents, and 120 each provided with a series of concentrically-arranged and equidistant lateral pins, in combination with escapement-levers arranged between the drums, and each provided with two pallets for the said pins, and with an 125 actuating-foot forming a part of the said lever, substantially as and for the purpose described.

9. A series of figured drums arranged to 130 turn separately and independently under the

action of springs or their equivalents, and each provided with a series of concentrically-arranged and equidistant lateral pins, in combination with escapement-levers arranged 5 between the said drums, and each provided with two pallets for the said pins, and with an actuating-foot forming a portion of the said lever, and with a trip-rod arranged to travel in relation to and operate upon and against

each and all the said levers, substantially as 10 and for the purpose described.

In testimony whereof I have signed my name to this specification in the presence of two subscribing witnesses.

MOSES G. CRANE.
